UNITED STATES PATENT OFFICE.

AUGUSTE PACHE, OF NEW YORK, N. Y.

COMBINED SPARK-PLUG AND PRIMING DEVICE.

1,242,367.

Specification of Letters Patent.

Patented Oct. 9, 1917.

Application filed May 3, 1916. Serial No. 95,264.

To all whom it may concern:

Be it known that I, AUGUSTE PACHE, a subject of Switzerland, residing in the city of New York, borough of Manhattan, county 5 and State of New York, have invented a certain new and useful Combined Spark-Plug and Priming Device, of which the following is a specification.

This invention is a combined spark plug 10 and priming device, and the salient object of the invention is to provide a device of the class described which will be extremely simple in construction, the parts of which may be readily dismantled for cleansing 15 purposes, and which device may operate to allow of the inflow of a priming fluid into an engine cylinder without the necessity of detaching any of the constituent parts of said device. A further object of the invention 20 is the formation of the main barrel of the spark plug from asbestos material, whereby the cost of manufacture is minimized and yet high efficiency results.

Features of the invention, other than 25 those specified, will be apparent from the following description, read in conjunction with the accompanying drawings.

In the drawings is illustrated one practical embodiment of the present invention, 30 but the construction therein shown is to be understood as illustrative only and not as defining the limits of the invention.

Figure 1 is a side elevation of a combined 35 spark plug and priming device embodying the present invention.

Fig. 2 is a vertical section therethrough, and

Fig. 3 is a detail elevation of the form of 40 firing electrically which I prefer to employ.

Referring to the drawings, A designates a metallic shell threaded, as at a, to screw into a threaded tap of an engine cylinder. The upper portion of shell A is interiorly threaded to receive an exteriorly threaded tubular 45 plug B which carries or supports the remaining portions of the spark plug and priming device.

Positioned within the plug B is the depending tubular stem c of an insulating block C, through which extends a tubular metallic bushing D. Bushing D is provided intermediate its ends with a shoulder d and said bushing is substantially frusto-conical in contour for a short distance above 55 the shoulder. The interior surface of plug B is also frusto-conical so that, when assem-

bling the parts B, C and D, the lower portion of the tubular stem c of the insulating block is distended, as shown in Fig. 2, to such extent as to wedge the parts tightly together and lock block C and plug B. The bushing D is held in the position shown to maintain the parts in assembled relation by means of a nut d', which is screwed onto the upper portion of the bushing D, the same being exteriorly threaded to coöperate with said nut. Nut d' seats on a washer d' superimposed upon the upper face of insulating block C.

Preferably formed integral with nut d' 70 and on the upper portion thereof, is a bowl-shaped vessel E, adapted to contain the hydrocarbon liquid for priming the engine, and said liquid is adapted to flow from the vessel E, through ducts e formed in the bushing D at the base of the vessel, into the interior passage of the bushing and down through and beyond the lower end of said passage into the interior of the shell A, thence passing directly into the engine cylinder. 75

As is generally the case in spark plugs, shell A, which threads into the top of the engine, is metallic and is, accordingly, in electrical connection with the casting of the engine, which is electrically grounded. The shell, therefore, serves as one of the electrodes of the ignition circuit, the other electrode being, in accordance with this invention, embodied in a detachable pin F slidably positioned within the tubular bushing D. 80

The pin F is shown in detail in Fig. 3 as embodying a metallic member, provided at one end with a threaded stem f, and adjacent cylindrical portion f', and at its opposite end with a reduced cylindrical portion f''. Adjacent the portion f'' is a portion f' which is preferably polygonal in cross section and extends from the portion f'' to a short distance from the portion f', and intermediate portion f' and f'' is a portion f'', of reduced cylindrical cross section. Upon the stem f is adapted to be positioned a thimble g, provided with a laterally extending arm g' carrying at its end an insulating knob G. The thimble seats on the upper end of the cylindrical portion f' and is securely locked in place by a jam nut g' screwed on the stem f. The interior of the thimble g is threaded and the threads thereof are adapted to coöperate with the 90

threaded portion of the bushing D which extends upwardly beyond the vessel E, as shown in Fig. 2. Thus, by rotating the handle G, the thimble is raised or lowered 5 upon the bushing D, with the result that the electrode F is raised or lowered. The cylindrical portion f' of electrode F is of such diameter as to snugly fit the interior bore of bushing D, and said portion f' is of 10 such length that, when the thimble g is screwed down tightly upon the upper end of said bushing, the portion f' will be depressed to such extent as to cover or seal the inner ends of the ducts e. The portion 15 f' thus serves as a plunger valve for controlling the flow of the priming fluid from the vessel E to the interior of the bushing. However, when it is desired to prime the engine, the handle G may be rotated to un- 20 screw thimble g and lift plunger f' to a position above the ducts e, thereby opening the ducts and allowing of the free circulation of the priming fluid. It has hereinbefore been stated that the portion f^2 of the 25 electrode F is polygonal in cross section, the purpose of this being to allow the priming fluid to circulate downwardly through the passage of the bushing about the polygonal portion, which, because of its shape, does 30 not entirely fill the cylindrical passage of said bushing.

It will, of course, be understood that, in completing the ignition circuit of the engine, the main from the magneto, battery 35 or coil is secured to the threaded stem, the other pole of the circuit being grounded, as is common.

From the foregoing description, it will be manifest that, for priming the engine, it 40 is not necessary to rotate the knob or handle G to such extent as to raise the plunger f' sufficiently to unseal the liquid ducts e, whereupon priming fluid deposited in the vessel E will pass through said ducts and 45 through the passage of the bushing D to the cylinder. Upon the conclusion of the priming operation, the thimble g is again seated by a counter-rotation of the handle G and the engine is free to carry out its normal 50 operations, it being understood that the spark occurs between the lower end of the electrode F and the lower edge of the shell A. Because of the threaded connection between plug B and shell A, the adjustment 55 may readily be made between the sparking parts.

It is thus unnecessary, in the carrying out of the priming operation, to detach any 60 of the parts, but merely lift the electrode F a short distance. As a matter of fact, no part is detached during this operation or left in such position that, if the charge is fired in the engine cylinder, the parts may be blown off with resulting damage, as has 65 frequently been the case in prior art devices.

However, if it were desired to clean the electrode F, the same may be readily removed or withdrawn from the bushing D by unscrewing the thimble beyond its priming position sufficiently to release the thimble from 70 the threads of the bushing. After removing the electrode F, the same may be cleansed of foreign matter and carbon and again properly positioned in the plug by reversing the detaching operation. 75

As hereinbefore stated, the insulating block C is preferably formed from asbestos. In spark plugs as heretofore constructed, it has been common to make the insulating portion of the plug from porcelain or mica. 80 In the first instance, the characteristics of the porcelain are such that a sharp knock will cause the brittle material to shatter and thus disrupt the plug. In the second instance, the mica is laid in very thin sheets 85 and subsequently cut to shape. This process is so expensive that only high priced plugs are constructed in this manner. I have found by experiment that asbestos may be employed in the manufacture of the in- 90 sulating portion of the plug, which asbestos may be pressed into shape to form an entire insulating block, or may be assembled in the form of thick disks super-imposed one upon the other. The resulting plug is 95 economical to manufacture, is properly insulated and is not open to objections inherent in the porcelain or mica plugs. Moreover, the exposed surface of the asbestos may be highly polished, thereby making the plug neat and pleasing in appearance. 100

It will be noted from Fig. 2 that the bushing D extends downwardly almost to the lower end of the plug and it thus forms 105 a guide for the electrode F. Accordingly, even though the reduced lower end f^2 of said electrode becomes highly heated, the electrode will not get out of plumb and short-circuit through the lower end of shell A. 110 This is an important advantage since it is well-known that the temper is drawn from the electrodes of the plug and a jar of the engine is likely to bend a long thin electrode sufficiently to short-circuit the plug at the 115 point where the spark normally occurs. This cannot result in the plug of this invention as the lower end of the bushing serves to steady the lower end of the electrode F, while in its heated condition. 120

Another marked advantage of the present plug over those of the prior art is the fact that there is no leakage of current in the asbestos insulating block and that the asbestos is not, in the least, affected by heat. 125 It is well-known that a large percentage of the breakage of plugs embodying porcelain insulating members is due to the fact that when the plug heats up, the expansion in the plug is unequal and this causes porce- 130

lain to break. This drawback, while common in porcelain plugs, is not inherent in those embodying mica insulating blocks, but in the latter case the plugs are apt to 5 become short-circuited by moisture working in between the sheets of mica, from which the insulating blocks are composed. Neither of the foregoing disadvantages is present in the plug of this invention, since heat has no 10 effect upon the asbestos and it is not the least affected by atmospheric changes.

Looking at the matter from a practical standpoint, the plug embodies many advantages, some of which have hereinbefore been 15 noted. However, an additional one may be mentioned in passing. It is frequently desirable to blow out an engine cylinder and this is generally accomplished by opening the pet-cock. In accordance with this in- 20 vention, however, the blowing out of the cylinder may be accomplished by simply elevating the electrode pin F to such extent as to unseal the ducts leading to the vessel E. This operation, while forming an out- 25 let from the interior of the cylinder, does not disturb the relative operative positions of the spark electrodes. Accordingly, when the ducts e are opened, as described, the engine may be operated and the explosions oc- 30 curring therein will exhaust, through the plug, any foreign matter such as grease, etc., which may be resident in the cylinder or in the plug. In many prior art plugs this operation is impossible since, in order to blow 35 out the engine through the plug, it is necessary to remove one of the electrodes. Accordingly, in a plug of such type a charge cannot be ignited in the cylinder when the plug is in priming condition.

Moreover, in many of the priming plugs heretofore used, a portion of the compressed charge of gas in the cylinder was free to enter the plug, with the result that the plug became unduly heated throughout its entire 45 extent. It will be noted, from Fig. 2 of the drawing, that this cannot occur in the plug therein shown for the reason that between the portions f² and f³ of the pin F there is a frusto-conical portion f⁵ which, when the 50 pin is in a depressed position, seats on a ledge d³ formed on the interior of the bushing D and near the lower end thereof. This seating of the frusto-conical portion f⁵ seals the bushing D at this point and precludes 55 the entry of the products of combustion or gaseous charges into the body of the plug.

It will be manifest from the foregoing description that the present invention embodies many features of novelty which, 60 when employed in combination, produce a priming plug of greatly increased efficiency. It will be understood, however, that many advantages of the invention may be obtained through the employment of some of 65 the features individually without necessa-

rily employing all. The invention is, therefore, to be understood as not limited to the specific showing made, but to be as broadly novel as is commensurate with the appended claims.

Having thus fully described the invention, what I claim as new, and desire to secure by Letters Patent, is:

1. In a device of the class described, a spark plug provided with a centrally disposed, longitudinally extending tubular metallic member, the upper end of which protrudes above the upper end of the plug, a liquid containing vessel surrounding the upper portion of said tubular member, ducts leading from the interior of the vessel to the interior passage of the tubular member, a thimble provided with a handle threaded upon the upper portion of the stem, and a fire pin extending through the passage of a tubular member and secured to the thimble, whereby the location of the thimble raises or lowers the pin, said pin being provided with a plunger portion adapted to closely fit the interior of the tubular portion to seal the ducts when said plunger is in depressed position and unseal the ducts when in an elevated position, thereby allowing liquid deposited in the vessel to pass through the ducts into and through the passage of the tubular member.

2. In a device of the class described, a spark plug provided at its upper end with a cup-shaped vessel, a tubular member extending longitudinally through the plug and vessel, and ducts through the wall of the tubular member opening communication between the interior of the vessel and the passage of said tubular member, whereby liquid deposited in the vessel is adapted to pass through said ducts and through the passage of the tubular member, in combination with a firing electrode positioned for longitudinal movement within the passage of the tubular member and provided near its upper end with a thimble having threaded connection with the upper end of the tubular member, a handle on said thimble for raising or lowering the same on the threads of the tubular member, and a plunger portion co-operating with said electrode and conforming in shape to the interior of the tubular member, whereby the raising of the electrode unseals the ducts from the vessel and the lowering of said electrode seals said ducts.

3. In a device of the class described, a spark plug provided at its upper end with a cup-shaped vessel, a tubular member extending longitudinally through the plug and vessel, and ducts through the wall of the tubular member opening communication between the interior of the vessel and the passage of said tubular member, whereby liquid deposited in the vessel is adapted to pass through said ducts and through the

passage of the tubular member, in combination with a firing electrode positioned for longitudinal movement within the passage of the tubular member and provided near 5 its upper end with a thimble having threaded connection with the upper end of the tubular member, a handle on said thimble for raising or lowering the same on the threads of the tubular member, and a plunger portion coöperating with said electrode and conforming in shape to the interior of the tubular member, whereby the raising of the electrode unseals the ducts from the vessel and the lowering of said electrode seals 10 said ducts, said sealing and unsealing operations being accomplished without releasing the threads of the thimble from the threads of the tubular member.

4. In a device of the class described, a 20 spark plug embodying at its lower end a metallic attaching shell and having at its upper end a metallic cup-shaped vessel, an elongated asbestos portion intermediate the shell and vessel, and a tubular metallic member extending longitudinally of the plug for securing the shell to the vessel, said tubular portion having ducts communicating with the interior of the tubular member and the interior of the vessel, in combination with a 25 firing electrode positioned for longitudinal movement within the passage of the tubular member and provided near its upper end with a thimble having threaded connection with the upper end of the tubular member, 30 a handle on said thimble for raising or lowering the same on the threads of the tubular member, and a plunger portion coöperating with said electrode and conforming in shape to the interior of the tubular member, whereby the raising of the electrode 35 unseals the ducts from the vessel and the lowering of said electrode seals said ducts.

5. In a device of the class described, a 40 spark plug embodying at its lower end a metallic attaching shell and having at its upper end a metallic cup-shaped vessel, an elongated asbestos portion intermediate the shell and vessel, and a tubular metallic member extending longitudinally of the plug for securing the shell to the vessel, said tubular portion having ducts communicating with the interior of the tubular member and the interior of the vessel, in combination with a 45 firing electrode positioned for longitudinal movement within the passage of the tubular member and provided near its upper end with a thimble having threaded connection with the upper end of the tubular member, a handle on said thimble for raising or 50 lowering the same on the threads of the tubular member, and a plunger portion coöperating with said electrode and conforming in shape to the interior of the tubular

member, whereby the raising of the electrode unseals the ducts from the vessel and the 55 lowering of said electrode seals said ducts, said tubular member extending below the asbestos portion to substantially the lower end of the plug to surround and guide the lower portion of the electrode and thereby 60 preclude short-circuiting of said electrode with the shell when the electrode is in a heated condition.

6. In a device of the class described, a 65 spark plug provided with a longitudinal passage, a vessel, ducts communicating with the vessel and said passage, a piston slidable longitudinally of said passage, an electrode movable with said piston, means for moving the piston to a position to close the ducts 70 from the vessel, and additional means co-operating with the electrode for closing the passage through the plug.

7. In a device of the class described, a 75 spark plug provided with a longitudinal passage, a vessel, ducts communicating with the vessel and said passage, an electrode mounted for sliding movement in said passage, said electrode being so formed as to normally seal the ducts from the vessel and 80 also seal the lower end of the passage to preclude the entrance of material into the lower portion of said passage as well as the upper portion thereof, a piston slidable longitudinally of said passage, an electrode 85 movable with said piston, means for moving the piston to a position to close the ducts from the vessel, and additional means co-operating with the electrode for closing the 90 passage through the plug.

100 8. In a device of the class described, a spark plug embodying an attaching shell, a collar having threaded connection therewith, the interior of said collar being upwardly tapered, an insulating member seated on the free edge of said collar and having a tubular stem extending into the interior thereof, a metallic bushing extending longitudinally through the insulating member and threaded at its upper end to receive a 105 securing member, said bushing being provided with a shoulder adapted to engage the lower edge of the tubular stem of the insulating member, and a portion of said bushing immediately above the shoulder being shaped in conformity with the interior of the collar, whereby, when the retaining member is screwed tightly upon the bushing, a portion of the depending stem of the insulating member is distended to such extent as 110 to securely lock the insulating portion and collar to the bushing.

115 In testimony whereof I have signed my name to this specification.

AUGUSTE PACHE.
